UNITED STATES PATENT OFFICE.

LEO R. LEWIS, OF SOMERVILLE, MASSACHUSETTS.

LOOSE-LEAF BINDER.

1,347,342.

Specification of Letters Patent. Patented July 20, 1920.

Application filed October 30, 1919. Serial No. 334,410.

To all whom it may concern:

Be it known that I, LEO R. LEWIS, a citizen of the United States, and resident of Somerville, in the county of Middlesex and State of Massachusetts, have invented new and useful Improvements in Loose-Leaf Binders, of which the following is a specification.

This invention relates to a loose-leaf binder or folder, and its object is to provide a simple, durable, efficient and inexpensive binder, which may serve either as a temporary or permanent binder for leaves, sheets, pamphlets or the like, and which will be easy to manipulate and of convenient form to handle whether used individually, or in a file or stack with other similar binders.

Certain embodiments of the invention are illustrated in the accompanying drawings, in which—

Figure 1 is an elevation, with one of the covers broken away, showing a binder embodying my invention, the covers being of light cardboard, or other flexible material;

Fig. 2 is a cross section, broken away, on line 2—2 of Fig. 1, showing one of the tabs holding a number of leaves in the binder;

Fig. 3 is an elevation of a binder having outside cover strips covering the back and straps;

Fig. 4 is a cross section, broken away, on the line 4—4 of Fig. 3;

Fig. 5 is a cross section, broken away, similar to Fig. 2 but showing the binder adjusted to a larger number of inserted leaves;

Fig. 6 is a cross section, broken away, showing a modification of the binder having covers of heavy, stiff cardboard or the like attached to the back;

Fig. 7 is an elevation, with one of the covers opened and broken away, of one side of a binder employing a tape as a fastener instead of a metal fastener; and

Fig. 8 is an elevation with one of the covers opened and broken away, of the reverse side of the binder shown in Fig. 7 showing the method of fastening the ends of the tape.

Referring first to the forms shown in Figs. 1, 2, 3, 4, and 5 of the drawings, 1 designates the covers of the binder or folder, and 2 the back, on which the two covers 1, 1, are folded. These parts, in the form now being described, are made of a single, inte-

gral sheet of paper, light cardboard, or other thin flexible material, folded upon itself. In the region of the binding edge are a number of pairs of longitudinal slots 5, 60 the two slots of each pair being disposed on opposite sides of the fold or middle of back 2. Two such pairs of slots 5 are shown in the drawings, but it will be understood that a single pair or more than two pairs of slots 65 may be provided, as required, depending on the size and purpose of the binder.

In substantial alignment with the slots 5 are scorings or creases 6, forming hinges on which the covers may be swung.

Straps 8 of tough paper, or other flat, flexible sheet material pass through the slots 5, with their body parts extending over the outside of the back of the binder, and their free ends extending through the slots to the 70 inside of the binder. The leaves 7 to be bound in the binder are fastened between the ends of the straps 8 by suitable fastening means such as metal staples or paper fasteners 12 which pass through perforations 10 in the free ends of the straps and holes 11 in the sheets or leaves to be bound. The fasteners 12 may be of usual form having a head at one end and prongs or shanks adapted to be bent and upset on the outer 85 side of the strap end. One or both of the free ends of the straps may be provided with a series of perforations 12, so that the straps, which are loosely and adjustably held in slots 5 will accommodate a larger or 90 smaller pack of leaves by shifting the fastener from one perforation to another. Instead of providing both ends of the strap 8 with a series of perforations, one end may have a single perforation and the other end 95 a number of perforations, in which case the entire adjustment may be made at one end of the strap; or only a single perforation may be provided in each end of the straps, and, for the convenience of the user, suitably spaced spots may be marked for making other perforations to accommodate 100 packs of inserted leaves of various thicknesses. The last mentioned arrangement has advantages especially when the binder is to 105 be used for a gradually growing pack of leaves, since the original perforations may be placed for binding a single leaf or a small number of leaves, and therefore in assembling the first leaves the user will not 110 place the fastener in the wrong perforations as he might do if a number were punched

out. The correct position of other perforations may be printed or otherwise indicated on the strap, and the user can punch the perforations out, and correspondingly adjust the fastener, as the pack of leaves grows.

In the simple form of binder shown in Figs. 1, 2 and 5, the straps 8, extending around the outside of back 2, are exposed to view, which is in most cases wholly unobjectionable, and in many cases may be an advantage because they can be made of colors contrasting with the cover and so be used as signals, or for classification purposes, when a number of binders are filed together. If it is desired to cover the straps, either for the purposes of appearances, or to protect them from injury, an outside cover strip 14 (Figs. 3 and 4) of paper, textile fabric, or other flexible, sheet material, may be fastened, as by cementing, to the covers 1, 1, and back 2, the area within lines $y-y$ being left uncemented so that the straps 8 will be free for adjustment lengthwise through the slots 5.

Instead of metal fasteners 12, other means may be used for fastening the leaves to the ends of the straps. For example, in Figs. 7 and 8 I have shown a flexible tape or cord 13 which extends between the perforations 13 of two strap ends with its ends threaded through the strap ends and the punchings of the leaves, and hitched around the free ends of the straps as shown in Fig. 8.

Fig. 6 illustrates the invention as embodied in a binder made with stiff covers 1^a, of heavy cardboard, or other similar material such as is used in ordinary bound books. The covers are attached to a flexible back 2, similar to the back part shown in the other figures, provided with slots 5 through which the straps 8 extend. If desired an outside cover strip 15 may be employed for covering and protecting the straps 8, secured to the covers 1^a and the back 2, unattached to the straps 8 which are left free for adjustment through the slots.

The covers 1 and straps 8 may be made of various colors, so that by combining different colors according to some arbitrary, predetermined plan, an almost endless number of combinations of colors may be made suitable for classifying the subjects matter of material filed in the binders.

In operation the fasteners 12 or 13 are unfastened from the straps 8 previously inserted through the slots 5, and leaves 7, having openings therein adapted to register with the openings 10 of the straps 8, are placed between the ends of the straps 8, and the fasteners 12 are inserted therethrough and the leaves are thereby fastened between the ends of straps 8. As the leaves 7 increase in number it will be necessary to unfasten the straps 8, insert the new leaves 65 and bring into operative position the proper

cooperating openings 10 in the ends of the straps and fasten the cooperating parts together with the fasteners. This operation is repeated as may be required until the capacity of the binder has been reached. It is evident, therefore, that efficient means is provided for quickly and securely binding between the covers of a binder loose leaves, such as sheet music or other leaves of a similar nature, combined with means for readily removing the leaves when desired.

The present invention provides a novel loose-leaf folder and light binder, suitable for correspondence, estimates, legal papers, notes, music, etc., which will always lie flat, and smooth; which has no rods, rings, springs or the like commonly found in temporary binders; which is inexpensive to make, and may be flexible or stiff as desired; which may be reversed inside out, and is equally acceptable if turned top for bottom or back for front; and which may be filed in a vertical filing system with the bound edge up if desired.

I claim:

1. A loose-leaf binder having a pair of slots in the region of its binding edge, and a strap of flat, flexible material extending over the outside of the binder between the slots with its free ends extending through said slots to the inside of the binder.

2. A loose-leaf binder having a pair of slots in the region of its binding edge, and a strap of flat, flexible material extending over the outside of the binder between the slots with its free ends extending through said slots to the inside of the binder, said free ends being perforated to receive fastening means by which loose leaves may be fastened between the ends of the strap.

3. A loose-leaf binder having a pair of slots in the region of its binding edge, and a strap of flat, flexible material extending over the outside of the binder between the slots with its free ends extending through said slots to the inside of the binder, one at least of said free ends having a series of perforations adapted to receive adjustable fastening means for fastening loose leaves between the ends of the strap.

4. A loose-leaf binder having a pair of slots in the region of its binding edge, and a strap of flat, flexible material extending over the outside of the binder between the slots with its free ends extending through said slots to the inside of the binder, said strap being loose in said slots and adjustable lengthwise.

5. A loose-leaf binder comprising two covers and a back and having a pair of slots in the region of its binding edge, the covers being hinged to the back on a line substantially in alignment with the slots, and a strap of flat, flexible material extending over the outside of the binder between

the slots with its free ends extending through said slots to the inside of the binder.

6. A loose-leaf binder having a pair of 5 slots in the region of its binding edge, and a strap of flat, flexible material extending over the outside of the binder between the slots with its free ends extending through said slots to the inside of the binder, and a 10 pack of leaves fastened between the ends of said strap.

7. A loose-leaf binder made of an integral piece of sheet material folded on itself to form two covers and a flexible back 15 and having a pair of slots in the region of its binding edge, and a strap of flat, flexible material extending over the outside of the back between the slots with its free ends extending through said slots to the inside 20 of the binder.

8. A loose-leaf binder made of an integral piece of sheet material folded on itself to form two covers and a flexible back and having a pair of slots in the region 25 of its binding edge and creased hinges substantially in alignment with said slots, and a strap of flat, flexible material extending over the outside of the back between

the slots with its free ends extending through said slots to the inside of the 30 binder.

9. A loose-leaf binder made of an integral piece of sheet material folded on itself to form two covers and a flexible back and having a pair of slots in the region of 35 its binding edge, and a strap of flat, flexible material extending over the outside of the back between the slots with its free ends extending through said slots to the inside of the binder, and a pack of leaves fastened 40 between the ends of said strap.

10. A loose leaf binder having a pair of slots in the region of its binding edge, a strap of flat, flexible material extending over the outside of the binder between the 45 slots with its free ends extending through said slots to the inside of the binder, leaves held in the binder by the free ends of said straps, and a flexible tape or cord to fasten the leaves passing through the straps and 50 having one end at least hitched around the free end of a strap.

Signed by me at Boston, Massachusetts, this 25th day of October, 1919.

LEO R. LEWIS.
